UNITED STATES PATENT OFFICE.

WILSON HARGREAVES, OF CHICAGO, ILLINOIS.

LATHING-MACHINE.

SPECIFICATION forming part of Letters Patent No. 663,434, dated December 11, 1900.

Application filed February 21, 1900. Serial No. 6,064. (No model.)

To all whom it may concern:

Be it known that I, WILSON HARGREAVES, a citizen of the United States, residing at Chicago, in the county of Cook and State of Illinois, have invented a new and useful Machine for Spacing Laths, forming series of the same into the form of gates and inserting lathing-nails therein, whereby the lathing of buildings may be improved and the cost reduced; and I do hereby declare the following to be a full, clear, and exact description of the invention, whereby a person skilled in the art can make and use the same, reference being had to the accompanying drawings and to the letters of reference marked thereon.

My invention consists in the construction, arrangement, and combination of the several parts and devices that will be hereinafter described and in the method or manner of moving the several parts by which the laths are spaced, held, and fastened in the form of gates and by which the distributing, conveying, holding, and driving of the nails into the laths are accomplished.

In the accompanying drawings of ten sheets, Figure 1 is a front elevation of my machine with the gate of laths and several parts of the machine in the position when the nails are driven and the tray and scoop are at their lowest position. Fig. 2 is a front elevation of the upper and lower pressure-slides with the several parts in position as shown in Fig. 1. Fig. 3 is a front elevation of the upper and lower pressure-slides with the upper slide raised and the several parts in the position when the nails have been driven and the lower pressure-slide is ready to be raised from the gate by the continued upward movement of the upper pressure-slide. Fig. 4 is a side view with the several parts to the left of the upright part of the frame in the position as shown in Fig. 1. The opposite side of the machine is similar to and symmetrical with the side here shown. Fig. 5 is a sectional side view with the several parts to the right of the center in the position as shown in Fig. 7. Fig. 6 is a sectional side view showing the several parts of the machine raised to their highest position, at which point the nails enter the feeding mechanism. Fig. 7 is a plan or top view with the rear part of the machine in the position shown to the left of the center

of sectional view Fig. 5. Fig. 8 is a sectional plan view through the line 8 8 in Fig. 5, showing the gate of laths in position in the machine when the nails are driven. Fig. 9 is a plan view of the sliding frame, rocking bars, and gate of laths as shown in the machine in Fig. 8. Fig. 10 is a plan view of part of the rocking bars shown in Figs. 8 and 9. Fig. 11 is a side view of the slides, stops, and springs in the rocking bars. Fig. 12 is a cross-section of the rocking bar and slide through the line 12 12, Fig. 10. Fig. 13 is a plan or bottom view of part of the rocking bar, the slides therein, and the links connecting the slides together. Fig. 14 is a side view of the cross-bars, the top view of which is shown in Figs. 8 and 9 in position across the series of laths forming the gate. The steel points shown in Fig. 14 are affixed alternately near opposite edges of the bar, by which arrangement their holding power is increased, rendering a diagonal bar usually placed on a gate unnecessary. Fig. 15 is a sectional view of Fig. 16 through the line 15 15. Fig. 16 is an enlarged plan view of part of the feeding mechanism hereinafter explained. Fig. 17 is a detail view of part of the feeding mechanism shown in Fig. 16. Fig. 18 is a view, partly in section, of the several parts shown in Fig. 6 through the line 18 18. Fig. 19 is a detail view of Fig. 18. Fig. 20 is a view of one of the parts of the nailing mechanism shown in position in Figs. 2 and 3. Fig. 21 is a sectional detail view of the lower pressure-slide and part of the feeding mechanism as shown in Fig. 6, with side view of part of Fig. 20 in position as shown in Fig. 2. Fig. 22 is a sectional view of the same parts, showing the change of position when the nail is driven as shown in Fig. 5. Fig. 23 is a back view of the upper and lower pressure-slides as shown in position in Fig. 2, the dotted lines showing the position of the upper pressure-slide in Fig. 3. This view shows the friction-springs affixed to the lower pressure-slide, the purpose of which is herein-after explained. The recesses in the frame A are to receive the points of the friction-springs when the positions of the slides are as shown in section Fig. 6. When said friction-springs enter said recesses, the pressure-slide E' is held secure till the downward movement of the upper slide E forces down the lower pres-

sure-slide E' and moves the friction-springs out of the recesses into the position shown herein. Fig. 24 is a detail view of the sectional parts shown in Figs. 21, 22, and 6.

- 5 In the several drawings, A designates the frame of the machine. B is the bed of the machine. B' is a sliding frame constructed to hold and move the laths while they are being formed into a gate and receive the nails.
- 10 b represents stops on the frame B' to regulate the widths of the gate. B² represents rocking bars held in the frame B' by trunnions. b' represents spacing-slides in the rocking bars B². b² represents links connecting the
- 15 b³ represents spacing-slides. b³ represents stops on the spacing-slides. b⁴ represents flat curved springs attached to the spacing-slides. b⁵ represents arms on B² in Figs. 8, 9, and 10. The foregoing parts are particularly shown
- 20 in Figs. 9, 10, 11, 12, and 13.

C represents laths spaced and held by the spacing-slides, stops, and springs, before described, and are shown in Figs. 1, 2, 3, 8, and 9.

C' represents cross-bars, of which there may be two or more, containing sharp steel points set diagonally therein, which enter and hold the laths when the bars are pressed on to form the gate, as shown in Figs. 9 and 14.

C² is a gage fixed to the bed of the machine

30 B to form a guide for the sliding frame B'. (Shown in Figs. 1, 2, 3, and 8.)

D is a presser-bar which moves vertically in the front of the frame A and is used to press the cross-bars C' onto the gate of the

35 laths. D is operated by the racks d, the pinions d', shaft d², and the lever d³. These parts are shown in Figs. 1, 4, 5, 6, and 8.

E and E' are the upper and lower pressure-slides. e represents links connecting E and

40 e' represents racks fixed by their extensions to the slide E. e² represents pinions on the shaft e³, which operate the racks e'. e⁴ is a lever by which the slides E and E' are operated. e⁵ represents roller-bearings back

45 of the racks e'. These parts are shown in Figs. 4, 5, and 6.

e⁶ represents friction-springs fixed on the back of the slide E', designed to hold the slide E' till the same is moved by the slide E. These

50 are shown in Fig. 23.

e⁷ represents pins in the slide E'. F represents bell-crank on the shaft e⁸. G represents telescopic connecting-rods pivoted to the bell-crank F and to the tray I. H represents automatic lifting-rods, also pivoted to the bell-crank F and constructed so as to fall

55 of their own weight against the pins i on the side of the tray I when they are in the position shown in Fig. 5. These movements are

60 shown in Figs. 4, 5, 6, and 7.

I is a tray in which the supply of nails is placed and is raised and lowered by the connecting-rods G and the lifting-rods H, as shown in Figs. 5, 6, 7, and 8.

65 i represents the pins on the side of the tray I which engage the lifting-rods H. i' represents straps on the side of the tray, which

guide and limit the movement of the lifting-rods H, as shown in Figs. 4 and 7.

J J are gravity-levers pivotally affixed to the under side of the tray I, the pivotal points being near the ends and to the side of the longitudinal center line of the levers. At the pivotal end of each of these levers a flat spring is affixed. The movement of these levers is limited by small stop-pins, against which the long ends of the levers fall with the rise and fall of the tray. In Figs. 1 and 4 the tray is shown in its lowest position, the long end of the levers resting against the stop-pins and the free ends of the flat springs at the short end of the levers being within the side lines of the tray. (See Fig. 1.) The levers and springs remain in this position while the tray is raised by the rods G to the position shown in Fig. 5, at which point in the upward movement the rods H fall under the pins i. As the tray is raised by the rods H from the position shown in Fig. 5 to the position shown in Fig. 6 the long ends of the levers fall to the opposite stop-pins. By this movement the springs on the short ends are swung out beyond the side lines of the tray and at right angles thereto. The levers and springs remain in this position while the tray is lowered. When the tray is part way between the highest point of elevation and the horizontal position, the rods H come in contact with the lever-springs, as they project beyond the sides of the tray. From the first point of contact till the tray reaches the horizontal position the rods continue to press back the springs of the levers, which are held in position by the stop-pins, against which the long end of the levers rest. As the weight of the tray is transferred from the rods H to the rods G by the continued lowering of the tray the rods are drawn below, and thus released from contact with the pins i and are instantly forced from under and to the side of the pins i by the pressure of the gravity-lever springs. The levers thus freed fall to the opposite stop-pins as the tray is lowered to the position shown in Fig. 1, where they remain till the movements here described are repeated.

K is a scoop hinged to the frame A of the machine by the scoop-bar k³. It is constructed to slide along the bottom of the tray I and scoop up the nails as the tray is raised from the horizontal position to its highest point. k' represents slots in K, into which the nails fall and pass into the feeding mechanism of the machine. k² represents openings in the scoop K, through which all nails not held in the slots k' pass back into the tray. k³ is a bar hinged to the frame of the machine and to which the scoop is attached. L is a swinging shutter hinged to the scoop-bar k³. Its purpose is to prevent the nails from jamming as they pass down the slots k' through the openings l in the bar k³ by partly closing the opening and by swinging out from the bar as the scoop is lowered with the tray, carrying with it as it swings all the nails resting

against it back into the tray. The construction of the scoop K is shown in Figs. 4, 5, 6, 7, 18, and 19 and the swinging shutter in Figs. 5, 6, 7, and 18.

5 M represents guideways affixed to the frame of the machine, forming a continuation of the slots k' when the tray is raised, as shown in Fig. 6.

N is a finger-bar held in extensions of the frame of the machine and free to move laterally in front of the lower end of the guideways M. n represents fingers attached to the finger-bar N, constructed and arranged to check the run of nails down the guideways M and to take one nail from the guideway at each movement of the finger-bar. The construction and operation of the finger-bar and fingers are shown in Figs. 1, 4, 5, 6, 7, 15, 16, and 17. N' is a trigger attached to the rack e' in Figs. 5 and 6. n' is a lever pivoted on the frame A, operated by the trigger N', as shown in Figs. 5 and 6. n² is a small bell-crank pivoted on the frame of the machine and connected by wires to the lever n' and to the finger-bar N, as shown in Fig. 1. n³ in Fig. 1 is a spring attached to the frame A and the bar N. These several parts are constructed and arranged to operate the finger-bar and fingers.

O is an apron arranged to throw the nails as they fall from the scoop back into the tray and to prevent them from passing into the working parts of the machine, as seen in Figs. 5 and 6.

P (shown in detail in Figs. 15 and 16) represents tubes firmly fixed to the frame A, each of which tubes has an opening near the top in line with the guideways M, which lead into them. In front of these tubes and through openings in the ends of the frames of the guideways M the fingers n pass and operate so as to allow one nail at a time to pass into the tubes P.

Q represents funnels attached to the bar q, which is hinged to the links e, attached to the slide E'. When raised, they form a continuous connection with the tube P. Their lower ends q' are partly closed by the lips q², which catch the heads of the nails as they fall. These parts are shown in Figs. 1, 5, 6, 21, 22, and 24.

R represents driving-bars attached to the upper pressure-slide E, constructed and arranged to descend behind the funnels Q, forcing the lips of the same from the heads of the nails and driving the nails into the laths C. The construction and operation of these parts are shown in Figs. 2, 3, 5, 6, 21, and 22.

S represents spring-cams affixed to the slide E, their position, construction, and operation being shown in Figs. 1, 2, 3, and 8.

T represents nail-holders pivoted on the lower pressure-slide E', so constructed and operated by the cams S as to hold the nails against the pins e' on the slide E' while the driving-bars R are forcing the lips of the funnel Q from the head of the nails and while

they are being driven into the laths, as shown in Figs. 1, 2, 3, 20, 21, and 22.

The operation of the machine is as follows: 70 The machine being placed in the position as shown in Fig. 4, a quantity of nails is put in the tray I. The lever e' is moved to the right, thereby operating the shaft e³ and the bell-crank F, lifting the rods G and tray I and drawing down the rods H, which fall against and engage the pins i in the sides of the tray I. When in horizontal position, as shown in Fig. 5, the lever e' being moved from right to left raises the tray I by the rods H to the 80 position shown in Fig. 6. While the tray I is being thus raised by the rods H, the scoop K moves along the bottom of the tray I underneath the nails therein, and as the tray and scoop rise to the position shown in Fig. 85 6 a part of the nails falls into the scoop-slots k' and the rest back through the openings k² in the scoop K back into the tray I, (see Fig. 7,) the apron O, Fig. 6, preventing them from falling into the other parts of the machine. 90 As the lever e' is again moved from left to right, drawing down the rods H and lowering the tray I, the shutter L swings from the scoop-bar k³, as shown in Fig. 5, throwing back all nails which may have been jammed in front 95 of the opening l in the scoop-bar k³. During the upward movement of the tray I from the position shown in Fig. 5 to the position shown in Fig. 6 the gravity-levers J fall toward the lowest part of the tray I, the springs attached 100 to the short ends of the levers projecting beyond the sides of the tray I, the reverse of the position shown in Fig. 1. As the rods H and the tray I are lowered these springs come in contact with the edges of the rods H and are 105 pressed back by these rods till the position shown in Fig. 5 is reached, where the rods H are drawn a little below the pins i and the pressure of the gravity-lever springs throw the rods H out of line with the pins i and allow the 110 tray I to be carried down by the rods G to the position shown in Fig. 4, in which position the gravity levers and springs are entirely within the lines of the sides of the tray, as shown in Fig. 1. They remain in this position till the 115 tray is lifted again to the horizontal and the rods H again engage the pins i and lift the tray to the position shown in Fig. 6. When the tray I and scoop K are lifted to the position shown in Fig. 6, the nails which fall into the slots 120 k' slide downward, and as they approach the shutter L and scoop-bar k³ they are brought into a steady and upright position head up by the peculiar bevel on the inside of the slots k'. (Shown in section in Figs. 18 and 19.) 125 Thus steadied, the nails pass under the shutter L, through the openings l in the scoop-bar k³, and down the guideways M, which are continuous with the slots k', till they are stopped by the fingers n on the finger-bar N, as shown 130 in Fig. 15. With the nails held in check in the guideways M by the fingers n and the several parts of the machine being in position as shown in Fig. 6 a movement of the lever e' to

the right operates the shaft e^3 , pinions e^2 , and racks e' and brings the several parts of the machine into the positions shown in Fig. 5, ready for the next movement, which feeds the 5 nails into the nailing mechanism. The lever e^4 is moved from right to left, raising the racks e' , to one of which the trigger N' is attached. As the racks are raised the pressure-slides E and E' are lifted vertically, together with the funnel-bar q and the funnels Q, to the positions shown in Fig. 6. During this vertical movement of the racks, slides, and funnels the trigger N' trips the lever n' , the movement of which communicated by 10 wire connection and small bell-crank n^2 to the finger-bar N moves it laterally to the right, the spring n^3 drawing it back to its first position. In this lateral movement of the finger-bar the first fingers are withdrawn from 15 the nails resting thereon, allowing them to fall on the lower or second fingers. The return movement of the bar N brings the first fingers between the first and second nails, (see Fig. 15,) checking them, while the second 20 fingers are withdrawn from the first nails, which drop into the tubes P and through the funnels Q to the end q' , where they are held, as shown in Fig. 6 and in detail in Figs. 21 and 24. The feeding mechanism described 25 operates with every movement of the lever e^4 from right to left, while the scoop supplies the nails to the guideways M but once whenever the lever e^4 is moved from left to right twice. The machine thus supplied with nails 30 and in position as shown in Fig. 6 is ready for driving the nails into the laths. These are placed on the sliding frame B' between the stops b^3 and springs b^4 , the series of laths being forced within the stops b , as shown in 35 Fig. 9. When thus spaced and held by the stops and springs in the rocking bars B², the cross-bars C' are placed across the laths C and the slide B' is moved under the presser-bar D, which, operated by the lever d^3 , racks d , 40 pinions d' , and shaft d^2 , presses the steel points of the cross-bars C' into the laths. These steel points being set in diagonal form hold the laths firmly in the form of a gate, as 45 shown in Fig. 9. The laths thus spaced and held on the sliding frame B' and by the cross-bars C' are moved into position to receive the first series of nails. When thus ready, the nailing mechanism and feeding tubes and funnels are as shown in position in Fig. 6 50 and detail Fig. 21. The movement of the lever e^4 brings the pressure-slide E down till it rests on the lower pressure-slide E', the latter being held in place by the friction-springs, which press into the depression 55 in the frame A, Fig. 23. In this movement the cams S force the nail-holders T against the nails, pressing them against the pins e^7 , Fig. 2, thus holding the nails firmly while the driving-bars R are passing down behind the 60 funnels Q, moving them outward away from the nails, as shown in Figs. 6, 21, and 22, till the bars R rest on the heads of the nails, as 65

in Fig. 22. The continued downward movement of the pressure-slides E and E' forces the nails into the laths, as shown in Figs. 1, 70 2, and 5. The next movement of the lever e^4 from right to left first raises the pressure-slide E, with the driving-bars R and cams S. The latter striking the upper incline of the nail-holders T move their lower ends from 75 the nails, as shown in Fig. 3, the lower pressure-slide E' remaining in place, held by its own weight and the resistance of the friction-springs e^6 , Fig. 23, till it is lifted by the links e and raised to the position shown in Fig. 6, 80 at which point the sliding frame is moved into position for the next series of nails, which are driven by again moving the lever e^4 from left to right, as before described. When the several series of nails have been 85 driven into the laths, the sliding frame B' is drawn from beneath the pressure-slides E and E' to the front extension of the bed of the machine B. The arms b^5 of the rocking bars B² are pressed down, raising the edge of the 90 rocking bars on their trunnions, releasing the gate of laths from the stops and springs, and the gate thus formed and prepared with nails is set aside ready for the lather. These gates of laths are arranged in packing-frames constructed for their safe and quick conveyance from the nailing-machine to the rooms or 95 building where they are required.

What I claim, and desire to secure by Letters Patent, is—

1. In a lathing-machine the combination of a frame A having a horizontal bed B and vertical standards joined at the top by a cross-piece having a series of guideways affixed thereto, with a nail-holding tray I hinged to 105 said cross-piece, a scoop pivotally attached to said guideways and having a series of inclines and slots corresponding with said guideways, its free end lying within and upon said tray and constructed to rise and fall with 110 it and to receive the nails from said tray and distribute them into said guideways; a cross-bar k affixed to said scoop at its pivotal end having a series of apertures l corresponding to and in line with the slots in the scoop K 115 and with the series of incline guideways M; a shutter L hinged to said cross-bar constructed to partly cover the holes l in the cross-bar k when the scoop is elevated by the tray and arranged to swing away from said 120 holes when the scoop is lowered; a pair of telescopic lifting-rods G pivotally attached to the tray I and to a bell-crank F arranged to raise said tray to a horizontal position; a pair of automatic lifting-rods H pivoted to 125 the bell-crank F and constructed to fall against and engage with the pins i on the tray I and to lift said tray from the horizontal to the highest position; a pair of gravity-levers J pivotally attached to the under side of the tray I, each lever having a flat spring, said levers being arranged to fall into position to engage and to release the rods H from their 130 engagement with the pins i on the tray I and

the bell-crank F, shaft e³ and the levers e⁴ as the means for operating said parts as described and for the purposes specified.

2. In a lathing-machine the combination of the frame A, guideways M, scoop K, its cross-bar k³ and shutter L and the tray I, together with the means for operating the same, as herein described and shown, with a finger-bar N arranged to move back and forth on the frame A at the lower end of the series of guideways M and transversely thereto; a series of fingers n attached to said finger-bar, constructed and arranged to check the flow of nails from the guideways and to allow one nail from each of the guideways to fall through conveyers to the nailing mechanism at each complete movement of the finger-bar, and the means, substantially as described and shown herein, for operating the said finger-bar as and for the purposes herein set forth and described.

3. In a lathing-machine, the combination with a frame A of two pressure-slides arranged to move vertically between the standards of said frame, said slides being connected with links and arranged with racks and pinions, and to be operated by a shaft and lever; a pair of friction-springs affixed to the back of the lower pressure-slide arranged to press against the standards of the frame A and to enter recesses therein and to hold the said pressure-slide at any point till moved upward by the links or downward by the upper pressure-slide; a series of nail-holders pivotally attached to the lower pressure-slide arranged to be operated by a corresponding series of spring-cams affixed to the upper pressure-slide, said nail-holders being constructed and arranged together with said cams and a series 40 of pins in the lower pressure-slide, to receive the nails from the conveyers and hold them in position to be driven, and a series of driving-bars affixed to the upper pressure-slide for driving said nails, all substantially as shown and described and for the purposes specified.

4. In a lathing-machine the combination of a frame A, a presser-bar D arranged to move

vertically in said frame, and mechanism for operating said presser-bar, with a sliding frame B' arranged to rest on the bed of the frame A, and to space and to hold a series of laths in the form of a gate while the cross-bars placed thereon are each firmly affixed to said gate of laths by the downward pressure of the bar D substantially as and for the purposes specified.

5. In combination with a lathing-machine a frame B' arranged to slide on the bed of the frame A having two or more rocking bars adjusted transversely therein, each of said rocking bars being provided with a series of small slides constructed to move longitudinally therein, said slides being linked together on the under sides, and each slide having a stop and spring on the upper side, all the several parts being constructed and arranged for spacing and holding a series of laths in the form of a gate while cross-bars are affixed and the nails are driven in the said laths as shown and described and for the purposes specified.

6. In a lathing-machine the combination with a frame having a horizontal bed, two vertical standards joined at the top with a cross-piece having a series of inclined guideways, of a nail-holding tray hinged to said frame, a scoop pivotally attached to said guideways and lying within said tray and the means, for operating said tray and scoop and filling said guideways with nails; a finger-bar and series of fingers arranged to move transversely to and in front of the lower ends of the series of guideways on the frame A and the means for operating said finger-bar and regulating the flow of nails to the nailing mechanism; a pair of pressure-slides arranged to operate vertically in the frame A, and a series of nail holding and driving devices, and the means for operating all the several parts hereinbefore shown and specified, substantially as described and for the purposes set forth.

WILSON HARGREAVES.
